UNITED STATES PATENT OFFICE.

AUGUST HILDT, OF NEW YORK, N. Y., ASSIGNOR TO L. DRYFOOS & CO., OF SAME PLACE.

DESIGN FOR A QUILTED FABRIC.

SPECIFICATION forming part of Design No. 17,092, dated February 8, 1887.

Application filed November 17, 1886. Serial No. 219,213. Term of patent 7 years.

To all whom it may concern:

Be it known that I, AUGUST HILDT, of the city, county, and State of New York, have invented a new and original Design for Quilting, 5 of which the following is a specification, reference being had to the accompanying drawing, which represents a portion of a strip of fabric quilted in accordance with my invention.

The design consists of the parallel lines *a*, between each two of which are included two rows of lines, *b c*. The lines *b* extend from and at right angles to one of the two lines *a* toward the other, stopping short of the latter, however. From the inner ends of these lines *b* extend up to and so as to join said last-referred- 15 to line *a* diagonal lines *c*. The lines *b* are of course parallel to one another; so, also, are the lines *c*.

What I claim, and desire to secure by Letters Patent, is—

The design for quilted fabric, consisting of parallel lines *a*, including in the field between each two of them a row of slanting or diagonal lines, *c*, parallel to one another, and a row of lines, *b*, which stand at right angles to lines *a*, 25 the two rows *b c* starting from opposite lines *a* and joining each other at their inner extremities, and each line *b* intervening between and joining the two lines *c* of contiguous fields, as described, and illustrated in the accompanying 30 drawing.

In testimony whereof I have hereunto set my hand this 9th day of November, 1886.

AUGUST HILDT.
